UNITED STATES PATENT OFFICE.

FRANK GOODIER, OF UPINGTON, CAPE PROVINCE, SOUTH AFRICA.

VACUUM SIPHON PUMP.

Application filed October 28, 1926, Serial No. 144,856, and in the Union of South Africa September 2, 1926.

The herein described invention which relates to a new or improved vacuum siphon pump has for its object and purpose a rapid means of emptying the contents of liquid containers, and particularly petrol and paraffin containers by the rapid and effective exhaustion of the air in the cylindrical barrel of the appliance partly by automatic and partly by mechanical means, thereby permitting the atmospheric pressure to act as the expelling agent in emptying the container of liquid.

In accordance with my invention I provide a cylindrical barrel or chamber open at one end and closed at the top by a cap screwed on or formed as part of the cylinder. Operating through this cap I provide a pump-rod connecting with a plunger or piston. Entering the cylinder in the upper portion I provide a delivery pipe and feeding into this delivery pipe a small diameter release pipe or vent from a point above the delivery aperture. Further I space around the circumference of the lower end of the cylinder inlets or apertures which, when the plunger or piston is at its lowest point, afford means for the contents of the container about to be emptied to flow into the cylinder, the liquid thus finding the same level inside as outside and in the process expelling an amount of air in the cylinder proportionate to the height of the contents of the container. Owing to the necessity for these apertures being above the plunger or piston they are a certain distance above the bottom of the container which therefore could never be completely emptied.

To overcome this disadvantage I place a collar round the base of the cylinder, so formed that while the upper edge of the collar is in close contact with the outside of the cylinder, there remains a space between the two which forms a continuation of the passage formed by the apertures aforementioned. This construction enables the maximum amount of liquid to be removed from the container.

As the circular edge of this collar might make too close contact with the bottom of the container and thereby restrict the flow of the liquid into the cylinder, I cut away a portion of it in a slanting direction.

I have shown how the liquid to be emptied is utilized to expel a part of the air in the cylinder. Now when the piston or plunger is raised through the length of the cylinder

it carries with it the column of liquid above it, more flowing in to take its place, until it reaches the delivery pipe after which siphonic action is established, but above the plunger or piston would still remain a small cushion of compressed air. To release this air and enable the plunger or piston to be drawn quite clear of the entrance to the delivery pipe I provide a small diameter pipe or vent between the cylinder top and the delivery branch. By this means the cushion of air is removed and the plunger or piston can be raised to the full height.

Finally I attach to the cap or form as a part of its conical projection for use as a piercer in opening a closed container. By making the diameter of this piercer slightly larger than the collar at the base of the cylinder an easy entrance of the pump into the container and a sufficient supply of air to replace the contents is assured.

In order that my invention may be readily understood and carried into practice, reference is hereby made to the accompanying drawing wherein Fig. 1 is a sectional elevation of the invention, portions being broken away to more clearly illustrate the construction. Figure 2 is a cross-section on line I—I of Fig. 1.

Referring to this drawing wherein like letters of reference indicate corresponding parts wherever occurring throughout the figure *a* designates the barrel or chamber to the head of which is suitably attached or may be formed as part thereof a cap *b* recessed to take a packing gland *c* provided with wings, lugs, or the like operating on packing *d* which ensures non-leakage around the pump-rod *e*.

To the lower end of the pump-rod *e* is attached the piston or plunger *f*. The lower end of the barrel or chamber *a* is encircled by a collar *g* which is in close contact at its upper circumference with the barrel but below that is separated from it by an air-space affording an inlet to the liquid which thence finds its way into the barrel or chamber by means of the perforations *h* in the wall thereof.

At the upper end of the barrel or chamber *a* is provided an aperture opening into a release pipe *j* which effects delivery into the overflow or main delivery pipe *k* of any air or liquid that may otherwise become compressed above the piston *f* in the upper portion of the cylindrical barrel *a*. At-

tached to the delivery pipe *k* is a clip, screw-union or other convenient means, a length of flexible tubing *l* which may or may not be provided with a suitable turncock as shown 5 at *m*.

For convenience in maintaining the invention in an upright position a clip *n* is provided for attachment to the wall of the container or for this may be substituted any 10 suitable spring type.

Attached to the cap *b* or formed as a part thereof is a piercer *o* whose greatest diameter is somewhat larger than the diameter of the collar *g*. By its use the container 15 is readily punctured and a hole made sufficiently large to admit of the easy insertion of the invention and at the same time to permit an adequate supply of air to take the place of the contents as they are removed.

20 In operation the container is opened by forcing the point of the piercer *o* through the top. The cylindrical barrel *a* is then inserted and held in position by the clip or spring *n*. The pump-rod *e* is then withdrawn to its limit and an instantaneous and continuous flow of liquid through the delivery pipe *l* results. Should it be desired to stop the flow temporarily, pushing the pump 25 rod *e* down until the piston or plunger *f* is below the delivery aperture will effect the 30 desired result.

This is made possible by the release pipe *j*. In the absence of this pipe a cushion of air would be compressed behind the piston when the latter is at the upper limit 35 of its stroke, which cushion would expand when the piston descends to a point below the delivery pipe, breaking the continuity of the liquid column, and interrupting the action of the siphon. If it is desired to maintain the siphonic action and yet not empty the container immediately, this can 40 be effected by fitting a suitable tap to the end of the delivery pipe *l* through which the contents can be drawn off as desired.

45 It will be seen that I have by my invention provided a new or improved vacuum siphon pump the use of which renders it possible to empty containers of liquid using only a single stroke of the pump-rod after 50 which a continuous flow ensues until a maximum quantity is removed, the amount remaining due to drainage from the pump etc. being so small as to be negligible.

The improvements herein set forth are 55 not limited to the precise construction and arrangement herein described, but may be embodied in various forms and modifications without departing from the spirit and scope 60 of the invention.

I claim:

1. A siphon pump comprising a cylinder barrel, a plunger operating in said barrel, an inlet adjacent the lower end of said barrel, an outlet adjacent the upper end of said barrel, the latter extending above the outlet a sufficient distance to form a recess for receiving said plunger, and an air release conduit opening into the barrel above said outlet connecting said recess and said outlet at a point in the latter below the uppermost point of said outlet.

2. A siphon pump comprising a cylinder barrel, a plunger operating in said barrel, an inlet adjacent the lower end of said barrel above said plunger when the latter is at the lower limit of its stroke, means forming a conduit externally to said barrel, communicating with said outlet and extending substantially to the level of the bottom of said barrel, an outlet adjacent the upper end of said barrel, the latter extending above the outlet a sufficient distance to form a recess for receiving said plunger, and an air release conduit opens into said barrel above said outlet connecting said recess and said outlet at a point in the latter below the uppermost point of said outlet.

In testimony whereof, I have signed my name to this specification at Upington this 30 tenth day of September, 1926.

FRANK GOODIER.
